DESIGN FOR A HANDLE OR THE LIKE FOR DOORS AND DRAWERS

Horace H. Raymond, Berlin, Conn., assignor to
The Stanley Works, New Britain, Conn., a corporation of Connecticut

Application October 31, 1936, Serial No. 65,619

Term of patent 14 years

To all whom it may concern:

Be it known that I, Horace H. Raymond, a citizen of the United States and resident of Berlin, in the county of Hartford, State of Connecticut, have invented a new, original, and ornamental Design for a Handle or the like for Doors and Drawers, of which the following is a specification, reference being had to the accompanying drawing forming a part thereof.

In the accompanying drawing:—

The figure is a perspective view of a handle or the like for doors and drawers showing my design. The opposite side of the article is of duplicate design to the illustrated showing.

I claim:

The ornamental design for a handle or the like for doors and drawers, as shown and described.

HORACE H. RAYMOND.
